United States Patent Office.

E. F. ANDERSON, OF MANSFIELD, CONNECTICUT.

Letters Patent No. 92,244, dated July 6, 1869.

TEACHERS' TOY.

The Schedule referred to in these Letters Patent and making part of the same.

To all whom it may concern:

Be it known that I, E. F. ANDERSON, of Mansfield, in the county of Tolland, and State of Connecticut, have invented a new and improved Toy; and I do hereby declare the following, when taken in connection with the accompanying drawings, and the letters of reference marked thereon, to be a full, clear, and exact description of the same, and which said drawings constitute part of this specification, and represent, in—

Figure 1, a side view, and in

Figure 2, a top view.

This invention relates to an improvement in toys, which serve both as an amusement and as an instructor, or object-teacher; and

The invention consists in the arrangement upon a revolving table of several revolving blocks, having figures upon their various sides, the blocks revolving independent of each other, and independent of the table.

In order to the clear understanding of my invention, I will fully describe the same, as illustrated in the accompanying drawings.

A is the base.

B, the table, supported upon a standard, C, and with a vertical shaft, D, centrally arranged through the table, and around which the table will freely revolve.

Above the table, at a suitable distance, I arrange a top plate, E, corresponding in form to the table below, and through the plate E, I pass spindles *a*, more or less in number, extending down into, and so as to be supported in the table below.

Between the table and plate, I arrange blocks F, more or less in number, upon the different sides of which, illustrations varying from each other are placed, the said blocks being arranged upon and supported by

the said spindles, and so as to turn freely, to present either side of the block out.

The revolving of the table and change of blocks afford amusement for the child, and as an object-teacher instructs the child as to the name of the illustrations upon the various sides of the block, by turning the block so as to present the required illustration upon the block to the front.

As an instructor, I prefer to add other blocks, G, upon the said spindles, with corresponding sides, and upon the several sides place the name of the illustration, as seen in fig. 1.

The blocks G turn independent of the blocks F, so that the child is required to arrange the blocks G with the names on the said blocks corresponding to the illustrations on the blocks F.

In addition to this, letters may be placed on the table or plate, as seen in figs. 1 and 2.

Having fully described my invention,

What I claim as new and useful, and desire to secure by Letters Patent, is—

1. The arrangement, upon a revolving plate, B, of several block upon spindles, so as to turn each block independent of the other and of the table, substantially as described.

2. The arrangement, upon a revolving table, B, of two or more series of blocks, F and G, each series revolving independent of the other series, and each block independent of the other block of the same series, substantially as described.

E. F. ANDERSON.
